UNITED STATES PATENT OFFICE.

JOHN R. FORTUNE, OF DETROIT, MICHIGAN.

FURNACE.

1,113,113.

Specification of Letters Patent.

Patented Oct. 6, 1914.

Application filed December 5, 1911. Serial No. 664,066.

To all whom it may concern:

Be it known that I, JOHN R. FORTUNE, a citizen of the United States of America, residing at Detroit, in the county of Wayne and State of Michigan, have invented certain new and useful Improvements in Furnaces, of which the following is a specification, reference being had therein to the accompanying drawings.

In the operation of automatic smoke consuming furnaces in which an arch plate is employed to support the arches over the fire chamber and through which arch plate air is supplied from the space between the arches to aid combustion, it is found that the air which is admitted to the air space between the arches at their forward end, tends to flow in streams through the space instead of being evenly distributed over the surface of the arch to cool the same and further that the air is unevenly supplied to the fire chamber throughout the length of the arch plate for the reason that upon increased resistance to the flow of air through one portion of the arch plate due to the banking of the fuel opposite that portion, the air will all flow to other portions of the plate and enter therethrough.

The object of this invention is to provide means for causing an even distribution of the air over the surface of the inner arch to evenly cool the same and prevent unequal expansion and consequent breaking down of the arch, and further to so conduct the air to the arch plate that the air will be evenly supplied to the fire chamber throughout the length of the arch.

To this end the invention consists in the matters hereinafter set forth and more particularly pointed out in the claims, references being had to the accompanying drawings, in which—

Figure 1 is a front end elevation of a furnace embodying the invention with portions broken away and in section to show the construction; Fig. 2 is a perspective view of the same with portions broken away to show the construction; Fig. 3 is a perspective detail of a portion of one of the arch plates and adjacent portion of the arches supported thereby; Fig. 4 is an enlarged transverse vertical section through an air inlet box; Fig. 5 is a longitudinal vertical section through the same; and Fig. 6 is a perspective detail of the air box with its top and slide shown separated therefrom.

In the drawings, a furnace of the usual general construction is shown having a front plate 1 and side magazines 2 extending rearwardly therefrom, the inner side of each magazine being formed by an arch plate 3 for supporting an inner arch 4 and an outer arch 5 which arches spring across the fire chamber 6 from one to the other of the arch plates and are spaced apart to form transverse air passages 7 between the transverse ribs or walls 8 which extend across the space between the arches and divide the same into a series of transverse air passages 7. Each of these air passages 7 communicates with the fire chamber through the arch plates which are each formed with passages 9 opening at their lower ends below the inner arch and through openings 10 into said passages at their upper ends.

Air is admitted to the space between the arches at the longitudinal center line of the outer arch by an air box 11 which is built into the outer arch 5 and extends longitudinally thereof from the front plate 1 to the extreme rear end of the arch. This air box comprises parallel side plates 12 built into the arch and spaced apart by transverse partitions 13 which are detachably held in place by tie-bolts 14. These bolts pass through the plates 12, one at either side of each projection and the partition is provided with a lug 15 extending laterally therefrom over one of the bolts to support the partition in place and when the nuts on the outer ends of the tie-bolts are turned up and the side plates drawn toward each other thereby the partitions are firmly clamped in place by said plates. These partitions are so located that each is positioned directly over one of the transverse ribs or walls 8 which divide the air space between the arches and thus air entering through the corresponding series of openings 16 in a cover plate 17 secured upon the top of the air box, is directed into the several passages 7 and conducted laterally in each direction from the air box to the arch plates. The top plate 17 is grooved at its under side to form a way 18 for a slide or damper 19 adapted to be moved longitudinally of the air box. This slide is made up of two parallel angle bars 20 connected by a series of plates 21 which are of a sufficient width to close the openings 16 when the slide is moved longitudinally. These plates 21 are spaced such a distance apart that the openings between

them are of a length equal to or greater than the length of the openings 16 so that when the slide is moved in an opposite direction these holes in the cover plate will be fully 5 opened leaving a free passage for the air therethrough. The slide is moved by the operator by means of a handle bar 22 secured to its forward end and extending through an opening in the front plate 1 of 10 the furnace.

By dividing the space between the inner and outer arches into a series of transverse air passages and connecting these air passages at the center of the outer arch with 15 the atmosphere, air is conducted into the space and evenly distributed over the surface of the inner arch to prevent unequal expansion thereof, and at the same time air is directed by these passages to the arch 20 plates throughout their length so that air will be evenly supplied to the fire chamber along the entire length of each arch plate. By providing the damper or slide to control the inlets of the several passages the amount 25 of air can be accurately regulated and the partial closing of the damper will control the flow of air to the fire chamber throughout the length of the arch plates as said damper controls all of the passages. In the 30 ordinary construction where the air is admitted to the space between the arches and is permitted to flow to any part of the arch plate throughout its length, the regulation of the air is difficult as when the air is partially shut off it will flow in the direction 35 of the least resistance or where there is the greatest draft, that is, to that part of the arch plate where the air passages therethrough are free and open and toward the 40 rear end of the arch plate where the draft is greatest.

Having thus fully described my invention what I claim is:—

1. In a furnace construction, inner and outer arches providing transverse air heating passages, and a longitudinal air inlet box forming the key of the outer arch and common to all of said passages intermediate the ends thereof.
2. In a furnace construction, an inner arch, an outer sectional arch, said arches providing transverse air heating passages, a longitudinal air inlet box forming the key

of said outer arch and having the arch sections seated in the side walls of said box, 55 said box being common to all of said air passages intermediate the ends thereof, and means movable longitudinally of said box for controlling the admission of air thereto.

3. A roof construction for furnaces, comprising an inner arch, an outer sectional arch, transverse walls between said arches and providing a series of air passages having open ends, an air box mounted between 65 the sections of the outer arch and constituting a key therefor, and partitions in said box providing air passages normally in communication with the series of air passages.

4. In a furnace having a fire chamber, the 70 combination with arch plates at the sides of the fire chamber formed with seats and air passages, of arches over the fire chamber seated upon said seats and having a series of transverse air passages between them communicating with the passages in the arch plates, a member in the outer arch at the longitudinal center thereof forming a series of inlets for the said passages between the arches, and a slide damper for said member 75 to control the flow of air therethrough.

5. In a furnace having a fire chamber, the combination with arch plates at the side of the fire chamber formed with seats and air passages, of an inner arch seated upon 85 said seats, an outer arch seated upon said seats with a space between it and the inner arch, transverse walls between the arches dividing said space into a series of air passages having the ends thereof communicating 90 with the passages in the arch plates, an air box in the longitudinal center of the outer arch and having the bottom thereof in communication with the transverse air passages and provided with transverse partitions above the transverse walls forming the air passages, a top on the box having openings, and a slide damper on the box to close 95 said openings.

In testimony whereof I affix my signature 100 in presence of two witnesses.

JOHN R. FORTUNE.
